US0D1082674S

(12) **United States Design Patent** (10) **Patent No.:** **US D1,082,674 S**
(45) **Date of Patent:** **** Jul. 8, 2025**

(54) **CHARGING STATION**

(71) Applicant: **Delta Electronics, Inc.**, Taoyuan (TW)

(72) Inventors: **Kai-Hung Huang**, Taoyuan (TW);
Chia-Chun Hsu, Taoyuan (TW)

(73) Assignee: **Delta Electronics, Inc.**, Taoyuan (TW)

(**) Term: **15 Years**

(21) Appl. No.: **29/897,407**

(22) Filed: **Jul. 14, 2023**

(51) LOC (15) Cl. **13-02**

(52) U.S. Cl.

USPC **D13/107**

(58) **Field of Classification Search**

(57) **CLAIM**

The ornamental design for a charging station, as shown and described.

DESCRIPTION

FIG. 1 is a perspective view of a charging station showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective reference view of the charging station in a use state.

The broken lines are for the purpose of illustrating portions of the charging station and form no part of the claimed design.

1 Claim, 9 Drawing Sheets
